Attorney

UNITED STATES PATENT OFFICE.

GEORGE A. WILKINS, OF AMSTERDAM, NEW YORK.

NEEDLE-MOUNT.

1,326,555.

Specification of Letters Patent. Patented Dec. 30, 1919.

Application filed November 30, 1917. Serial No. 204,481.

To all whom it may concern:

Be it known that I, GEORGE A. WILKINS, a citizen of the United States, residing at Amsterdam, county of Montgomery, and 5 State of New York, have invented certain new and useful Improvements in Needle-Mounts, of which the following is a specification.

Reference may be had to the accompanying drawing, and the reference characters marked thereon, which form a part of this specification. Similar characters refer to similar parts in the several figures therein.

This invention relates to means for mounting knitting-needles for use in a knitting-machine, such for example as a cylindrical spring-needle knitting-machine, wherein the needles are mounted in fixed relation to the cylinder.

20 The principal object of the invention is to dispense with the leads in which such needles have heretofore been commonly mounted.

Other objects will appear in connection 25 with the following description.

Figure 1 of the drawings is a view in side elevation, partly in section, of a needle-mount embodying my invention, the members of the mount being separated as for 30 the insertion or removal of a needle.

Fig. 2 is a view in side elevation of a knitting-needle adapted for use with said mount.

Fig. 3 is a view in side elevation of the 35 needle-mount with the members closed together, clamping therebetween a knitting-needle.

Fig. 4 is a vertical cross-section of a knitting-machine cylinder and clamp-block with a needle and needle-mount embodying my 40 invention clamped therebetween.

Referring to the drawings wherein the invention is shown in preferred form, 1 and 2 are the members of the needle-mount, said members being hinged together at 13.

45 The member, 1, is formed on its outer side with a surface, 3, adapted to engage the cylinder, 4, of a circular knitting-machine, and is provided on its inner side with a longitudinal groove, 5, adapted to receive the 50 shank, 6, of a knitting-needle, and is also provided with an opening, 7, intersecting said groove and adapted to receive the offset end, 8, of said needle-shank.

The member, 2, of the needle-mount is 55 adapted to be swung open as shown in Fig.

1, to permit the insertion and removal of needles; and to be swung closed as shown in Fig. 3, to clamp the shank of the needle in said groove 5.

Said needle-mount preferably corresponds 60 in external form and dimensions with the ordinary lead in which spring-needles are commonly mounted, whereby it is adapted to be used in association with or in place of said leads in making up a needle-cylinder. 65

The member, 2, thus has a surface, 9, adapted to be engaged by a clamp-block, 10, removably secured to the cylinder by means of a screw-bolt, 11.

My improved needle-mount is thus adapted 70 to be clamped between the needle-cylinder and the clamp-block, 10, as shown in Fig. 4, in the same manner that the ordinary needle-lead is so clamped; and when my improved needle-block is so clamped 75 upon the cylinder of the machine, the clamp-block, 10, serves to securely hold the members, 1 and 2, together, clamped upon the shank of the needle which is inclosed between them. 80

To make repair of a broken needle, all that is necessary is to unscrew the screw-bolt, 11, remove the clamp-block, 10, and swing open the member, 2, of the needle-mount which supports the broken needle, replacing the same with a new needle, after which the member, 2, is swung to a closed position, the clamp-block, 10, replaced and the screw-bolt, 11, screwed up tight. 85

While I have referred to the part 4, as 90 the cylinder, and the part 10, as a clamp-block, it will be understood that said parts may be any parts similar to those between which lead-mounts for knitting-needles are ordinarily clamped in a knitting-machine. 95

I have shown the members, 1 and 2, hinged together, but for certain purposes of the invention they may be made relatively movable in any known manner.

The members of the needle-mount may 100 be made of any desired material, but I prefer to employ steel or other metal as the mount so constructed will be of a permanent nature and not easily broken or worn, and thus will form a most substantial support for the 105 needles.

While I have described my invention as applied to cylindrical knitting machines, it will be understood that the form of the member of the machine upon which the 110

needles are carried is immaterial, and that the invention is equally applicable to cylindrical and to straight knitting machines.

What I claim as new and desire to secure by Letters Patent is—

The combination with the cylinder of a knitting machine; a clamp-block; and a screw-connection between said clamp-block and said cylinder, said cylinder and clamp-block being adapted to clamp therebetween ordinary needle-supporting leads; of a needle-mount interchangeable with said leads interposed between said cylinder and

said clamp-block, said needle-mount comprising hinge-connected members, one having a cylinder-engaging-surface and the other a clamp-block engaging surface corresponding to the similar surfaces on the needle-supporting lead; and a knitting-needle removably clamped between said hinge-connected members.

In testimony whereof, I have hereunto set my hand this 23rd day of November, 1917.

GEORGE A. WILKINS.
